UNITED STATES PATENT OFFICE

2,305,523

REAR END CONSTRUCTION

Herbert J. Framhein, Chicago, Ill., assignor to
The Yale & Towne Manufacturing Company,
Stamford, Conn., a corporation of Connecticut

Original application July 21, 1938, Serial No.
220,432. Divided and this application January
8, 1941, Serial No. 373,578

6 Claims. (Cl. 180—75)

This application is a division of my application Serial No. 220,432, filed July 21, 1938, now Patent No. 2,244,875, and disclosing an improvement in the well known Walker rear end drive, shown in the patents to Carroll, No. 1,570,941, and Blakeslee, No. 1,919,925, owned by the Walker Vehicle Company. For convenience, in this application I shall use those reference numerals that are used in my earlier application, to denote the same parts.

As a feature of my invention, I have adapted the rear end of the Walker drive so that it will lend itself for cooperation with modern disk wheels of small diameter using low pressure tires of considerable width. For this purpose, I mount at each end of my rear end housing a gear case of special design, adapted to be rotated as a unit by a drive shaft. Each gear case is formed, preferably, by the securing together of a main casing plate and a secondary casing plate. The main casing plate carries the disk wheel, which is secured thereto preferably by a series of bolts extending circularly around the outside face of the plate. The brake drum is also secured to this same main plate. In addition, the internal gear of the Walker wheel drive is secured to this main casing plate. Because of this relation of the parts, the braking stresses as well as the driving stresses are transmitted through a minimum of joints, contributing thereby a really valuable structure. The seemingly simple structural changes involved are the result of a very radical revision in the relationship of the parts of my wheel construction, and mark a departure from an old and well defined practice, all as will be appreciated from a study of the art.

Also, because of the relation of the wheel fastening means to the gear case, a single form of dished disk wheel may be used to give three wheel combinations. Thus, when the disk wheel is applied with its dished portion in one position a relatively narrow tread results, while when the wheel is reversed it yields a wider tread. Also, two wheels may be used together with their dished portions facing in opposite directions.

I shall now refer to the drawings wherein is shown a preferred modification of my invention. In the drawings, Fig. 1 is a partial section and elevation of a rear end housing of a Walker drive showing the wheels and tires and gear casing at one end thereof. Fig. 2 is a vertical section through that portion of Fig. 1 illustrating the

wheel mounting. Fig. 3 is a partial section along lines 3—3 of Fig. 2.

Referring now more particularly to the drawings, and especially Fig. 1, reference numeral 10 indicates a rear end housing which is formed of two halves suitably united in a manner which forms no part of this invention. An armature 11 of suitable commercial construction is formed about a hollow shaft 12, which shaft is formed 15 at one end integrally with a flange 13, or may be united to that flange 13 as by welding. The flange 13 forms substantially half of a differential casing, designated generally by reference numeral 15, the other half of the casing being formed from a member 16 substantially the same in shape as the flange 13, the member 16 terminating in a hollow shaft portion 17. The two parts 13 and 16 of the housing 15 are united by a series of bolts 18, or in any other way that may be preferred. When so united, the hollow shaft portion 17, the two parts 16 and 13, and the hollow shaft 12 form a single unit.

The shaft portion 17 is supported through bearing 19 on a bearing support 20 extending 25 from housing 10, the bearing assembly being of suitable commercial form, the specific construction being not important here. The other end of the hollow shaft 12 is supported in a bearing support 21 through bearing 22 much in the same manner as is supported the shaft portion 17. A commutator quill is forced on to the hollow shaft 12, and supports commutator segments 24 for rotation integrally with the armature 11, all as will be quite readily understood by those skilled in the art. In the arrangement so far described, armature 11 will rotate with the hollow shaft 12 on bearing 22 at one end, and relatively to bearing 19 on bearing support 20 at its other end, through the intermediary, of course, of the hollow shaft portion 17. This will rotate the differential casing 15 and the mechanism associated therewith, all as is fully illustrated and described in my earlier application, whereby to rotate the oppositely extending drive shafts 27 and 28.

Referring now to Figs. 2 and 3, I show a preferred construction of the gear casing of my invention, and the mounting of the disk wheels and the brake band thereon, whereby the braking and driving stresses are transmitted through a minimum of joints. Also, in Figs. 2 and 3 I illustrate the manner in which I mount either one or both of oppositely dished disk wheels on the gear casing of my wheel construction. I shall describe the mounting of the gear casing and

its wheels at but one end of the housing, it being understood that the said mounting is exactly the same at both ends.

The rear end housing 10 of the Walker drive is saw-cut as at 40 so that there may be inserted a suitable stub axle 42, which is keyed to the housing at 43, and is secured against endwise movement in the housing by a pin 44. The stub axle is further held by binding of the housing thereto through the bolt 45 which passes through the two ears 46 extending from the saw-cut portion of the housing, and draws the housing together. The stub axle 42 terminates at 47 just short of a hub cap 48. Two pairs of ears 49 extend diametrically from the stub axle, these ears being secured as by welding at 50 to the stub axle. Between the ears of each pair of ears, there extends a bearing shaft 51 which in turn supports an idler gear 52 through suitable roller bearings. The pair of idler gears 52 thus carried on the pairs of ears 49 are driven by a pinion 53 which is formed on the drive shaft 28. The idler gears 52 are in turn in driving relation to a ring gear 54.

This ring gear is mounted about the inner periphery of a gear casing designated generally by reference numeral 55. The gear casing 55 is formed of a secondary casing plate 56, and a main casing plate 57, the two being joined to one another and simultaneously to the ring gear 54 by a series of bolts 58. The gear casing thus formed is supported at one side thereof through the plate 56, by a bearing 59 on the stub axle 42. At its other or outer side, the gear casing 55 is supported through its main casing plate 57 on the bearing 60 relatively to the outer end of the stub axle 42. The hub cap 48 previously described is mounted on screw threads 61 formed on the main plate 57 of the gear casing and covers the end thereof, it being provided with a threaded plug 62 normally closing an opening through which lubricating material may be inserted.

From the structure so far described, it will be readily appreciated that when the drive shaft 28 is rotated, it will through its gear pinion 53 rotate the idler gears 52, which in turn will rotate the ring gear 54 and therefore the gear casing 55, this rotation of the gear casing 55 being about the stub axle 42. It is well to note that the driving torque is submitted directly to the main casing plate 57.

The main casing plate 57 of the gear casing 55 is formed with a series of built up portions 63 threaded for a series of bolts 64 on which are secured the disk wheels 65, to be described later. Due to the shape of the main casing plate 57 and therefore of the gear case, the bolts 64 will be secured in comparatively close relation to the extension of the stub axle 42. Because of the placing of the bolts in the positions indicated, made possible through the proper shaping of the gear casing, the disk wheel 65 having a relatively wide flange may be used, despite the fact that the disk wheel itself is of small diameter. This is of importance in the particular assembly, and is one of the contributing features making it possible, in an electric drive of the Walker type, to use disk wheels with relatively wide pneumatic tires.

A brake drum 70 is also secured directly to the main casing plate 57 by a series of bolts 71. This is made possible by the shape of the said main casing plate 57 and its relation to the entire assembly. Braking force applied against the drum 70 will thus be transmitted to the tire on wheel 75

65 through a minimum of parts and connections. The construction I have thus shown and described, I have actually found resists effectively any loosening of the parts incidental to the application of driving and braking stresses.

As pointed out previously in this specification, I use a type of disk wheel designated by reference numeral 65, secured through securing lugs 66 and nuts 67 on the series of bolts 64. I may use one 10 wheel applied as is the right hand wheel of Figs. 1 and 2, or as is the left hand wheel of Figs. 1 and 2. If I wish, I may use two wheels as shown. Thus, also, because of my wheel construction, I need stock but one type of disk wheel, and yet 15 provide customers with three different wheel mounting combinations.

The advantages of my construction will now be clearly understood. Since it will be quite apparent that my contribution may be embodied 20 in specific forms other than herein shown, I do not wish to be limited therefore to any one form, but desire rather that my monopoly be limited only as required by the state of the art.

I claim:

25 1. A rear end construction of the class described comprising a housing, a stub axle supported at each end of said housing and terminating outwardly of said housing in two pairs of ears, an idler gear supported on each pair of ears, a gear casing, bearings on said stub axle at each side of said pairs of ears, said gear casing being mounted for rotation about said stub axle on said bearings, an annular ring gear secured about the inner periphery of said gear casing and driven by said idler gears, a series of wheel securing bolts spaced circularly on the outer side of said gear casing and substantially inwardly of the outer periphery of said gear casing, said gear case being so shaped that a suitably dished disk wheel secured to the outer surface of the gear casing through said bolts may extend inwardly so that the tire on said disk wheel will be substantially in the plane of said ring gear, while another disk wheel oppositely dished and secured to said gear casing by said bolts will extend in an opposite direction and substantially out of the plane of said ring gear.

40 2. A rear end construction of the class described comprising a housing, a gear casing mounted for rotation relatively to said housing, means in said housing for rotating said gear casing relatively to said housing, a main plate forming part of said casing and having a series of threaded bores, a tire carrying wheel, a series 45 of bolts in said threaded bores securing said wheel directly to said main plate, and a brake drum also secured with a circular surface thereof applied directly to said main plate.

55 3. A rear end construction of the class described comprising a housing, a gear casing mounted at each end of said housing for rotation relatively to said housing, power means whereby said casing is rotated relatively to said housing, a main casing plate forming part of said gear casing, a series of wheel securing bolts spaced circularly in a series of threaded openings formed in the outer side of said main casing plate, a tire carrying disk wheel secured directly to the main casing plate through said bolts, and therefore to said gear casing, and a brake drum secured with a circular surface thereof applied directly to said main casing plate by a second series of bolts.

60 4. A rear end construction of the class described comprising a housing, a gear casing

mounted at each end of said housing for rotation about said housing, a main casing plate and a secondary plate secured to one another to form said gear casing, an annular ring gear secured to the inner surface of said main casing plate, power means in said housing whereby rotation is imparted to said gear casing through said ring gear, a series of wheel securing bolts spaced circularly on the outer side of said main casing plate, a tire carrying wheel secured directly to said main casing plate by said bolts and therefore to said gear casing, and a brake drum for said gear casing bolted with a circular surface thereof applied directly to said main casing plate.

5. A rear end construction of the class described comprising a housing, a stub axle supported at each end of said housing and terminating outwardly of said housing, a gear casing comprising a main casing plate and a secondary plate, bearings on said stub axle whereby said gear casing is mounted for rotation about said stub axle, an annular ring gear bolted to the main casing plate about the inner periphery of said gear casing, means extending through said 10 stub axle for driving said ring gear and thus rotating said gear casing, a series of wheel securing bolts spaced circularly on the outer side

of said main casing plate, a tire carrying disk wheel having a circular disc portion secured to the said main casing plate by said bolts, and a brake drum bolted with a circular surface thereof applied directly to said main casing plate.

6. A rear end construction of the class described comprising a housing, a stub axle supported at each end of said housing and terminating outwardly of said housing in two pairs of ears, an idler gear supported on each pair of ears, a gear casing comprising a main casing plate and a secondary plate mounted for rotation about said stub axle, an annular ring gear secured directly to said main casing plate and about the inner periphery of said gear casing and driven by said idler gears, a series of wheel securing bolts spaced circularly on the outer side of the main casing plate of said gear casing in a series of threaded openings, a tire carrying disk wheel having a disk portion fitting against said main casing plate and secured directly to said main casing plate by said bolts, and a circular brake drum bolted with a circular surface thereof applied directly to the said main casing plate.

HERBERT J. FRAMHEIN.
